HYDRAULIC POSITIONING SERVO SYSTEM
Frederic Lissau, 24-15 27th St., Astoria, N.Y.
Filed June 25, 1959, Ser. No. 822,774
9 Claims. (Cl. 121-41)

This invention relates to a hydraulic system for controlling apparatus, and more particularly to a hydraulic positioning servo system.

The prior art for this invention is to be found in the text "Oil Hydraulic Power and Its Industrial Applications" by Ernst, on page 309, where FIG. 242 shows a flow divider valve. The flow divider valve, or flow control, may be compared to an electrical component, such as a Wheatstone bridge. Referring to this figure, which for the sake of discussion is illustrated in the drawings of this application, the illustration has been identified according to the text, and if P2 exceeds P1 the valve will move to the left, decreasing resistance R4 and increasing resistance R3. This will cause P1 to approach and finally equal P2. The fluid flow through each leg of the bridge as illustrated is determined by the equation

$$P0 - P1 = Q1R1$$

$$P0 - P2 = Q2R2$$

Since P1 must equal P2 at all times, the right sides can be equated, therefore

$$Q1 = R2$$

$$Q2 = R1$$

The flows Q1 and Q2 are independent of the pressures in the system. If resistances R1 and R2 are made exactly equal, the flows in each leg of the bridge will be equal, regardless of loads L1 and L2, either of which may be zero.

The text above identified, according to this figure, shows a flow from Q to either side of the flow divider and out legs L1 and L2, whereas applicant's device is a reverse flow, that is applicant provides a flow to the center of the flow divider, and in turn to either end of the flow divider out of two legs similar to L1 and L2.

Prior art includes the servo valve manufactured by Cadillac Gauge Co., and identified as their Series FC200. In this particular valve, shown as FIG. 1 in their catalog, they use a flapper valve that is electrically operated and controlled. This flapper valve is used for a displacement of the ratio flow divider. The operation of the flapper valve controls the displacement of the spool valve illustrated, and the spool is displaced proportionally. In this valve with an axial load the pressure deteriorates. This is because the flow will be throttled by the motion of the spool valve in such a way as to drop the pressure on the side opposing the load. In the Cadillac valve the pressure is fed to both ends of the spool and there is thus provided an orifice at each end where the fluid passes through to the flapper valve. The movement of the spool valve is not similar in any sense to the repositioning of the piston as in applicant's device. In the Cadillac valve the spool movement is limited to a small displacement. In this valve, the spool cannot resist any load, further the spool is not connected to any other member, it moves perfectly free, and in this valve, for proper functioning of the flapper valve, it is necessary that the flow be directed against the flapper.

The prior art illustrates various positioning servo systems, but in each instance the servo system is either electrically operated or a combination of hydraulic and electric or a hydraulic system with a mechanical feedback, whereas it is an object of the present invention to provide a remote controlled positioning servo system comprised entirely of hydraulic components.

2

All prior art discloses the position of a valve (in the form of a spool) which acts as a governing element, whereas it is an object of this invention to provide a cylinder primarily designed to perform a force displacement relationship.

It is a further object of this invention to provide a hydraulic servo system in which there is provided a hydraulic cylinder with a linear position seeking piston therein, and in which a fluid pump is connected through a ratio flow divider to opposite ends of said hydraulic cylinder.

A still further object of this invention is to provide a hydraulic servo system in which there is provided a hydraulic cylinder with a linear position seeking or non-position seeking piston therein, and in which a fluid pump is connected through a ratio flow divider, and the ratio flow divider in turn to a sensing null unit and in turn to opposite ends of said hydraulic cylinder, and in which said position seeking piston is in turn connected to a piston in a power cylinder that is either in alignment or in parallel with said first cylinder, and a second fluid pump may be connected through an amplifier valve to opposite ends of said power cylinder, and said amplifier valve is controlled in its movement by the sensing element of the null unit.

It is a still further object of this invention to provide a hydraulic servo system, in which there is provided a circular hydraulic cylinder with a position seeking rotor therein, and in which a fluid pump is connected through a ratio flow divider to opposite sides of said rotor in said hydraulic cylinder.

A still further object of this invention is to provide a plurality of hydraulic cylinders, in which each cylinder is provided with a linear position seeking piston therein, and in which a fluid pump is connected through a ratio flow divider to opposite ends of each hydraulic cylinder.

A still further object of this invention is to provide a plurality of hydraulic cylinders in which each cylinder is provided with a linear position seeking piston therein, and in which a fluid pump is connected to a plurality of ratio flow dividers, and in which all of the ratio flow dividers may be synchronized by a single element, and in which each ratio flow divider is utilized with one of said hydraulic cylinders by connecting said ratio flow divider to opposite ends of said cylinder.

A still further object of this invention is to provide a plurality of hydraulic cylinders in which each cylinder is provided with a linear position seeking piston therein, and in which there is provided a ratio flow divider connected to each cylinder at opposite ends thereof, and in which there is provided a pump that is connected to the first ratio flow divider to effect the operation of the position seeking piston in the first cylinder, and in which the fluid flow out of said first cylinder is in turn connected to the ratio flow divider of the next cylinder, and in which each subsequent ratio flow divider and cylinder are similarly connected and in which said linear position seeking pistons will be operated in series.

A still further object of this invention is to provide a plurality of hydraulic cylinders in which each cylinder is provided with a linear position seeking piston therein, and in which there is provided a ratio flow divider connected to each cylinder, and in which there is provided a pump that is connected to each ratio flow divider and in which said linear position seeking pistons will be operated in parallel relationship.

A still further object of this invention is to provide a hydraulic servo system in which there is provided a hydraulic cylinder with a linear non-position seeking piston therein, and in which a fluid pump is connected through a ratio flow divider to opposite ends of said hydraulic cylinder.

A still further object of this invention is to provide a hydraulic servo system, in which there is provided a circular hydraulic cylinder with a non-position seeking rotor therein, and in which a fluid pump is connected through a ratio flow divider to opposite sides of said rotor in said hydraulic cylinder.

It is a further object of this invention to provide a hydraulic fluid servo system in which there is provided a fluid flow divider, and in which a hydraulic cylinder with a linearly positioned piston therein is connected from either end of said cylinder to either end of said flow divider, and in which a fluid pump is connected to a central inlet on said hydraulic cylinder to produce a capillary flow over said piston to either side of said cylinder and in turn to either side of said flow divider and to be discharged from the single outlet of said flow divider.

Other objects of this invention shall be apparent by reference to the accompanying detailed description and the drawings in which:

FIG. 1 is a schematic, partially in cross-section, of a linear position seeking hydristor system;

FIG. 2 is a schematic, partially in cross-section, of a non-position seeking hydristor system;

FIG. 3 is a schematic, partially in cross-section, of a rotary position seeking hydristor system;

FIG. 4 is a schematic, partially in cross-section, of an unbalanced linear position seeking hydristor system;

FIG. 5 is a schematic, partially in cross-section, of a ratio flow divider;

FIG. 6 is a schematic, partially in cross-section, of a further embodiment of FIG. 1;

FIG. 7 is a schematic, partially in cross-section, of a still further embodiment of FIG. 1;

FIG. 8 is a schematic of a still further embodiment of FIG. 1;

FIG. 9 is a schematic of a still further embodiment of FIG. 1;

FIG. 10 is a schematic, partially in cross-section, of a further embodiment of FIG. 1;

FIG. 11 is a schematic, partially in cross-section, of a still further embodiment of FIG. 1;

FIG. 12 is a cross-sectional view of a further embodiment of FIG. 3;

FIG. 12A is a cross-sectional view taken on line 12A—12A of FIG. 12;

FIG. 13 is a cross-sectional view of a further embodiment of FIG. 2;

FIG. 14 is a cross-sectional view of a still further embodiment of FIG. 2;

FIG. 15 is a schematic of a further embodiment of a non-position seeking hydristor;

FIG. 16 is a cross-sectional view of a further embodiment of FIG. 3;

FIG. 17 is a cross-sectional view of a further embodiment of a non-position seeking hydristor;

FIG. 18 is a schematic, partially in cross-section, of a servo system with position seeking hydristor;

FIG. 19 is a schematic of a load compensated power system;

FIG. 20 is a schematic showing a sub-system which may be added to FIG. 18;

FIG. 21 is a schematic showing a prior art reference; and

FIG. 22 is a schematic showing a further embodiment of this invention.

Referring to the drawings and particularly FIG. 1, there is illustrated a hydraulic cylinder 10, in which there is mounted a piston 11. The piston is provided with a piston rod 12 that extends either side of said piston and passes through a rod bearing or aperture 14 at either end thereof. The cylinder 10 is provided with three ports, a central outlet port 15 and a pair of inlet ports 16 and 17, ports 16 and 17 being positioned adjacent the opposite ends of said cylinder 10. It is to be noted that the outlet

port 15 is in fact a circular groove or opening surrounding the center of said cylinder.

It is to be noted that piston 11 may be provided with very slight clearance or with fairly large clearance from the walls of the cylinder 10, and due to the piston rod 12, piston 11 will be maintained in a concentric position at all times. The clearance between the piston 11 and the inner wall of cylinder 10 is to permit the flow of the hydraulic fluid from either side of the cylinder over the surface of the piston and out through the outlet port 15. This device as described shall be referred to hereinafter as the hydristor. Hydristor, being a coined word, may be defined as a mechanical assembly such as a hydraulic cylinder with a piston mounted therein, a fluid inlet pressure port at each end and a fluid return port at the center of said cylinder. The piston is fitted within the cylinder with enough clearance to allow a capillary flow or leakage past the piston. The piston member is displaced as a function of output position, there are two complementary resistances created, R1 and R2; their ratio R1/R2 is therefore a function of output position. Each of the resistances is connected in series, that is through the legs or pipes to opposite ends of the ratio flow divider 30 or with similar resistances r1 and r2, which are created in reverse order in the ratio flow divider as a function of input position, so that the pressure p1 and p2 in the legs or pipe connections equal each other if

$$\frac{R_1}{R_2} = \frac{r_1}{r_2}$$

Thus, it is the purpose of the hydristor to utilize the pressure differential p1 and p2 as a remote input signal or error signal. Since the pressures p1 and p2 are created by the input setting of r1/r2, it would be equally correct to state that the ratio r1/r2 is used as the input signal, and the pressure differential P1 and P2 as the error signal. There are two types of hydristors; I is a position seeking type, and II is a non-position seeking type. With the position seeking hydristor, both ends of the cylinder are closed to allow the fluid to act on the area at the end of the piston. When the pressure on each side of the piston is equal, the piston will be in equilibrium. It is apparent that as the pressure on either side changes, the piston will seek a new position.

Referring to FIG. 2, there is illustrated a non-position seeking type of hydristor that is comprised of a cylinder 20 with both ends open. Mounted within the cylinder is a double piston 21. The double piston is formed with two equal piston exterior surface areas 22 and 23, spaced from each other but connected by a rod 24. Piston 21 is provided with a seal 25 at either end thereof, cylinder 20 is provided with three ports, an outlet port 26 and two inlet ports 27 and 28. The inlet ports are provided as a circular groove or opening surrounding the piston, and should be positioned about the center of the normal linear movement of the piston, whereas the outlet port is positioned at the center of cylinder 20 adjacent the open area surrounding rod 24.

It is to be noted that with the nonposition seeking type, both ends of the cylinder are open and the piston is in reality two spaced equal displacement pistons that are joined by a piston rod, leaving an open area in the center of the cylinder adjacent the outlet port. Both pistons may be provided with a seal over their outer ends, and the inlet ports must be positioned about the lineal center of each piston. The fluid that is normally fed in through the inlet ports 27 and 28 will leak or seep or flow from each inlet port toward the outlet port (center) providing a complementary hydraulic resistance whose ratio is a function of the displacement of the moving member (two pistons). The non-position seeking hydristor does not provide any effective pressure areas.

The hydristor lends itself to many variations in design and structure and also to many application in use, and of course, the hydristor whether of type I, position

seeking, or II, non-position seeking, is not usable or operative as a single element, but must be considered as a part of a system or combination of component parts, depending upon the particular problem.

The simplest combination for the position seeking hydristor is with a ratio flow divider 30, FIG. 1. The ratio flow divider may take the form of a three ported body 31, the inlet port 32 at the center, and both outlet ports 33 and 34 equally spaced from center (laterally); a central bore 35 is fitted with a slidable piston 36, the piston is provided with an enlarged central portion 37 to divide the flow, and is also connected to rod 38 extending in a linear direction through either end of the body to allow physical movement of the flow dividing body 37. A pump 40 is connected to a fluid supply 41 and thus the fluid pressure outlet of said pump is in turn connected to the inlet port 32 of the ratio flow divider 30. With the flow dividing body 37 centrally positioned there is an equal flow to both outlet ports 33 and 34 and the hydristor will receive an equal flow to each inlet port 16 and 17 and remain in equilibrium; however, if the rod control 38 is moved laterally right or left the flow is divided in an unequal proportion, depending upon the degree of movement and in turn the fluid flow to the hydristor is effected, one inlet receiving a greater flow than the opposite inlet and effecting an unbalance or movement of the piston until a static position is reached.

Referring to the ratio flow divider 30, the position of the central portion 37, which is generally spool shaped with an angular land 42 on one side and 43 on the other, provides an everchanging opening between the land 42 or 43 and the associated edge 44 of the body 31. Thus, there are provided two complementary openings, one on either side of the central body 37, which we may refer to as L1 and L2. The magnitude of each opening divided by a constant C forms the hydraulic resistances r1 and r2. Thus,

$$r_1 = \frac{L_1}{C} \text{ and } r_2 = \frac{L_2}{C}$$

It is to be noted that the hydraulic constant C may be affected by the viscosity of the fluid, temperature of the fluid, diameter of the spool or central body, etc. It is obvious that the ratio of the two complementary resistances r1/r2 is independent of this constant, since

$$\frac{r_1}{r_2} = \frac{\frac{L_1}{C}}{\frac{L_2}{C}} = \frac{L_1}{L_2}$$

Therefore, the ratio of the resistances r1 and r2 equals the ratio of the displacement L1 and L2, and is independent of all other variables.

It is to be noted, referring to FIG. 1, that the hydristor creates two complementary resistances opposing the flow of the two pressure legs r1 and r2, whose ratio is a function of the displacement of the hydristor piston 11 so that

$$\frac{R_1}{R_2} = \frac{L_1'}{L_2'}$$

Referring to FIG. 1, and particularly the piston 11, it may be desirable to increase the flow or leakage over the piston to the outlet 15. It may not be desirable to increase the clearance of the piston. The leakage or flow may be readily increased by inserting one or more lateral slots 13 along the surface of piston 11. Thus the piston 11 may be maintained in its lateral position with only the desired clearance for movement within the cylinder and the lateral slots 13 may provide the desired flow.

The same combination of hydraulic components used in FIG. 1, with the position seeking hydristor, may also be used in FIG. 2, with the non-position seeking hydristor, that is the inlet ports 27 and 28 may be connected to the ratio flow divider 30 by ports 33 and 34, and the ratio flow divider, in turn, may be connected to

the pump 40 through port 32. With the device so connected, the non-position seeking hydristor can be used as a feedback element to attain position control.

Referring to FIG. 3, there is illustrated a rotary position seeking hydristor 50. This is similar to the linear hydristor shown in FIG. 1, except that the hydraulic cylinder in this example takes the form of a circular housing 51 closed at either end thereof, with a circular aperture 52 at either end thereof. A stationary partition 53 is provided that is affixed to body 51 and bears against the edge of a rotor 54. Rotor 54 is pivotally mounted in the circular apertures 52 at either end of body 51 and extends through these apertures to provide a rotary piston rod or drive shaft on either side of the body 51. Rotor 54 is also provided with a semicircular body 55 of a diameter slightly less than the internal diameter of body 51. The clearance between the outer periphery of this body and the inner periphery of body 51 provides the necessary clearance or space for the flow of fluid from the area on either side of the partition 53 to an outlet port 56. A pair of inlet ports 57 and 58 are provided adjacent either side of partition 53. The rotary position seeking hydristor 50 is combined with the other hydraulic components namely the ratio flow divider and fluid pump, in the same order as described in FIG. 1, so that with a fluid flow from the pump through the ratio flow divider, fluid will flow into the chambers on either side of the partition 53, and with equal pressure on either side thereof, the rotor body 55 will maintain the position as illustrated in FIG. 3, with the fluid leaking, seeping or passing over the surface of the rotor body 55 to the outlet port 56 and thus being expelled. It is apparent as in FIG. 1, when rod 38 is moved to the right or left that the fluid pressure on either side of partition 53 will be changed and there will no longer be an equilibrium. Thus, with an increase in pressure on one side and decrease on the opposite side, rotor body 55 will be rotated to a new position until a static balance is obtained. This degree of rotation is utilized by apparatus not shown in the same manner in which 40 degree of linear movement of piston 11 may be utilized as shown in FIG. 1. With the rotary position seeking hydristor two effective areas, A1 and A2, may be effected by pressures in leg 1 (inlet 57) and leg 2 (inlet 58) creating the motive forces for the hydristor piston and piston rod. The areas A1 and A2 do not have to be of the same magnitude, as the hydristor can also be operable with the piston rod protruding from one side only.

Referring to FIG. 4, there is shown what may be termed an unbalanced hydristor. In form, it is quite 50 similar to that shown in FIG. 1, except that piston 11 is provided with a single piston rod 14, which protrudes through one end of cylinder 10. The unbalanced hydristor is designed specifically for one type of installation and that is where response in one direction should be 55 faster and/or with more power than in the opposite direction. In this example, the piston 11, under the influence of a differential pressure, will move in the direction of the lower pressure until equilibrium is obtained. The equilibrium position of the hydristor piston with 60 no load applied depends on the ratio r1/r2. Due to the unequal areas a differential pressure must exist for equilibrium. The equilibrium position of the piston is modified proportionally and in the direction of the load. The hydristor piston rod will give under a load and the contact pressure of the hydristor piston rod can be varied 65 by changing the ratio r1/r2. The effective Area A (FIG. 4) used for motive power can be combined with the hydristor 10 to form a position seeking hydristor. The pressure differential p1-p2 thus will act on the effective area of the hydristor piston 11 and seek to move the piston 11 into the desired position. Under a load the piston 11 will reposition itself to a new position which will be proportional to the load. The hydristor 10 (FIG. 4) can also be used as a feedback element in a servo 70 system.

Referring to FIG. 5, there is illustrated an enlarged detail of the ratio flow divider 30 of FIG. 1. The ratio flow divider may be of an unbalanced design so that the operator may actually feel any transfer of position. The unbalance is due to the design without the balancing pistons. Even with this design, the movement of rod 38 can create a hydraulic balance, a point at which no load is felt. However, if a load is applied on the hydraulic piston immediately the balance will be changed and the operator may feel the load on the signal input rod 38.

Referring to FIG. 6, there is illustrated a plurality of hydraulic cylinders 10, similar to those illustrated in FIG. 1, and a ratio flow divider 30 and a pump 40. In this embodiment, the ports 33 and 34 of the ratio flow divider are connected in parallel, that is port 33 is connected to each of the ports 16 of the hydristor 10 while port 34 is connected to each of the ports 17 of the hydristor 10. Thus, with this arrangement, when the ratio flow divider 30 is in equilibrium, the fluid flow will be equal to each of the hydristors and as in the previous embodiment any movement of the control rod 38 will change the proportionate flow increasing or decreasing the flow to the opposite sides of the various hydristors. Of course it is apparent that any change will produce an equal response on each hydristor.

Referring to FIG. 6, it is obvious that if a load is applied to the piston rod of one of the hydristors, its $R1/R2$ ratio will change. With this change, the pressures $P1$ and $P2$ will also change. Thus, a new flow pattern will be superimposed on the pattern set up by $R1/R2$ for the remaining hydristors. For example, if a load is applied on the piston 14' of hydristor #2, then the piston rods of hydristors #1 and #3 will reposition themselves since the fluid will take the path of least resistance with the motors connected in parallel, moving upward by a distance proportional to the load applied on piston rod 14' of hydristor #2. This general arrangement or application of the device may be, for example, a remote reading pressure transducing device where one piston 14' is the pressure transducer and the other piston may be connected to gauges measuring the force or pressure.

Referring to FIG. 7, there is illustrated a cross-sectional view of a ratio flow divider 30'. In this embodiment, the design of the original flow divider 30 shown in FIGS. 1 and 6 is simply multiplied. There are three central bores 35' and there are three slideable pistons 36, one in each bore, and there are three connecting rods 38, each one connected to the slideable piston 36, and the three connecting rods 38 are in turn joined to a single control rod 38'. Each bore 35 is provided with the same configuration as in FIGS. 1 and 6 and with the same porting. However, it is to be noted that in the enlarged body 31', the inlet port 32 from the pump must be ported from the one bore 35' to the next bore 35' and again ported to the third bore 35', so that the fluid flow will be to the center of each bore 35, as shown in FIG. 7. The ratio flow divider 30' thus provides (in this instance) three controls or ratio flow dividers which may be of the unbalanced design, each one being connected to a separate hydristor. The importance of this embodiment is in the use of a multiplicity of position seeking hydristors where there are different individual loads. In this embodiment, the interaction as in the above embodiment is eliminated, the ratio flow dividers may be actuated in unison and they will have equal effect if the ratio flow dividers are identical or if the ratio flow dividers are varied, having different sizes and creating different displacement, the actuation of the ratio flow dividers in unison can produce a sequence of different displacement patterns in the hydristors to which they are connected. This embodiment provides a predetermined positive displacement in each hydristor. This illustrates that it is not load compensated.

Referring to FIG. 8, in which there is a duplication of the general arrangement of pump, ratio flow divider and position seeking hydristor shown in FIG. 1, this duplication is provided for a purpose, that is where it is desirable to produce a series of similar controls. The series of components will be controlled by a three independent single input signal or movement of the control rods 38", which is physically connected to affect in equal degree each ratio flow divider. The effect of this signal produces a change in hydristor #1. Similarly each signal produces a change in hydristors #2 and #3. If there is a small flow with high pressure we would use a series circuit, but if there is a large flow of low pressure we would use them in parallel.

A still further embodiment, is illustrated in FIG. 9, in which the same components are utilized, that is a pump, a plurality of ratio flow dividers 30 and a plurality of position seeking hydristors. In this instance, the pump is connected by a single line to the inlet port of each ratio flow divider 30 to provide an equal flow and to provide that flow at the same time. The ratio flow dividers 30 are connected in the same fashion as illustrated in all of the previous embodiments to the hydristors. Thus, in this embodiment, the input signal produced by the movement of rod 38 for each ratio flow divider may be considered individually.

Although we have described FIGS. 6, 7, 8 and 9 with relation to a linear position seeking hydristor, it is understood that this includes any form of hydristor that shall be included herein.

In addition to the various combinations of hydristors, ratio flow dividers and pump, there are a number of variations in the design of the position seeking hydristor, the non-position seeking hydristor and the ratio flow divider.

Referring to FIG. 10, in which there is illustrated a linear position seeking hydristor 10', which is a further embodiment of FIG. 1, in this embodiment all of the components are similar but piston 11' is, in this embodiment, provided with a central bore 19 larger than the piston and a bore 18 of equal diameter at either side thereof, slightly smaller than the diameter of the piston, and as in FIG. 1 the connecting rods 12 and 14 are similarly passed through the cylinder and piston extending to a position where the movement of piston 11' may be utilized to control an auxiliary device. In this embodiment, the piston 11' is provided as a tapered piston, that is, tapered toward either end; the taper being designed to provide a flow from minimum to maximum. This design permits a greater proportional flow than that illustrated in FIG. 1.

Referring to FIG. 11, there is illustrated a still further embodiment of the position seeking hydristor as illustrated in FIG. 1. The cylinder 10 in this embodiment is provided with an inner cylinder 9 that is in fact a porous material. The piston 11 is mounted within cylinder 9, and to permit the installation of cylinder 9 within cylinder 10, the ports 16 and 17 may be moved to enter the opposite ends of cylinder 9. The porous cylinder 9 may be designed to provide a very small or fairly large seepage or flow therethrough.

Referring to FIG. 12, there is illustrated a further modification of FIG. 3. In this figure, there is provided a rotary type hydristor and since the degree of movement of the rotor in FIG. 3 is limited to slightly less than 180° , FIG. 12 provides a rotor that will permit the movement of slightly less than 360° . The hydristor 50' is of a circular housing or body 51' with a circular aperture 52 at either end thereof, a stationary partition 53, that is affixed to the body 51 and extends laterally the length of the body and bears against the edge of a rotor 54. Rotor 54 is pivotally mounted in circular apertures 52 at either end of body 51', and extends through these apertures to provide a rotary piston rod or drive shaft on either side of the body 51'. Rotor 54 is also provided with a blade

55'. The blade 55' does not extend to the internal surface of housing or body 51'. Instead there is provided a circular partition 59, which extends from either end of said body 51' and is provided with a slot 59' at the lineal center of said body. It is also to be noted that the ports 57 and 58 must extend through housing 51' and through the circular partition 59 on either side of the stationary partition 53. Thus, in operation, with an equal flow on either side of partition 53, the rotor 54 will be moved so that blade 55' is in an upright position (as shown in dotted lines, FIG. 12), and of course the fluid flow will be through the slot 59' and out the outlet 56. A change in the proportionate flow may move the rotor to a position as illustrated and of course the control of the rotor will be to a degree of slightly less than 360°.

FIG. 13 illustrates a further embodiment of the non-position seeking hydristor illustrated in FIG. 2. In this embodiment, the piston 31 has been modified with a central body 21' of smaller diameter than the internal surface of the cylinder and the piston 21' is provided with three enlarged portions 22' and 23' at either end thereof and 24' at the center of said piston. The port 26 is also connected to a lateral slot 29 in juxtaposition with the surface of enlarged portion 24', and approximately equally spaced either side of center. Thus, with this design, the fluid flow in ports 27 and 28 will not be interrupted by the movement of piston 21' but the position of the enlarged portion 24' will be in proportion to the flow from inlet ports 27 and 28.

FIG. 14 illustrates a still further embodiment of the non-position seeking hydristor illustrated in FIG. 2. In this embodiment, the cylinder 20' becomes a movable reciprocating sleeve while the piston 21'' becomes a stationary supporting element. The porting to this further embodiment is also changed, that is the inlets 27 and 28 are positioned at either end of the stationary piston 21'' and the outlet port 26 is eliminated, as the fluid will escape through either end of the cylinder or sleeve 20' and drop by gravity into the sump positioned below the cylinder. The piston 21'' is provided with two bores, one bore 27' leading from port 27 to a cross bore 27'' while a bore 28' leads from the port 28 to a cross bore 28''. The cross bores 27'' and 28'' are positioned either side of a central seal 25', seal 25' being positioned at the center of piston 21'' and surrounding the periphery of the piston to prevent fluid flow past the central portion of the piston. The cross bores 27'' and 28'' may be recessed at the periphery of the piston or a circular groove may be provided in the periphery of the piston. It is apparent that in any operation with ports 27 and 28 connected to a radio flow divider, as in the previous embodiments, that fluid flow through ports 27 and 28 will pass through the bores 27' and 28', through the cross bores 27'' and 28'', and due to the seal 25', the fluid will seep or leak between the piston exterior surface and the internal surface of the cylinder or sleeve 20'.

FIG. 15 illustrates a still further embodiment of the non-position seeking hydristor illustrated in FIG. 2. In this embodiment, the components are slightly different although the method of operating is similar to that of the device illustrated in FIG. 2. The cylinder is replaced by a pair of identical complementary valves 90 and 91. These valves are fairly simple in structure, that is, a simple cylinder 92 with a reciprocal piston 93 mounted therein. The piston 93 is provided with an upper reciprocal guide 93' and a lower poppet valve portion 93''. The piston is retained open or in contact with cam 96 by a spring 97. Cylinder 92 is provided with a bore for the upper portion 93' of piston 93 and an enlarged chamber 92' with a valve seat at the bottom of this chamber to receive the poppet valve portion 93''. It is to be noted that the inlet is below the poppet seat, while the outlet is above the poppet seat. Piston 93 is provided with a connecting rod 94, there is an inlet port at one end and an outlet port at the other end. The inlet port of valve

90 may be connected to the same inlet 27 as in the previous embodiment, and the inlet port of valve 91 may be connected to the inlet port 23 as in the previous embodiment. The outlet port of each valve may be interconnected to a common outlet port 26 as in the previous embodiments. The connecting rod 94 may be provided with a roller or ball 95. A cam 96 is positioned to abut with both of the rollers or balls 95. Cam 96 is supported by rod 97 and rod 97 in turn may be supported in a pair of bearings 98 at either side of said cam 96. It is to be noted that cam 96 is comprised of two cone shaped surfaces with the bases abutting at the center so that the rollers 95 may roll against the surface of the cam on either side thereof. Rod 97 may be connected to an auxiliary device such as a power cylinder. The operation of the device is somewhat similar to the embodiments already described, in that the fluid flow from a ratio flow divider will provide the flow through inlet ports 27 and 28. This is a non-position seeking hydristor, and the cam 96 is necessarily a linear cam that is moved horizontally by a power cylinder (not shown). The valves 90 and 91 are balanced valves. The position of the linear cam 96 will depend upon the fluid flow from the ratio flow divider and of course this flow, in addition to being connected to the balanced valves 90 and 91, will also be connected to the power cylinder (not shown), thus any movement of the linear cam 96 by the power cylinder will be similarly reflected in the position taken by the balanced valves. That is, in the event the greater flow is through inlet 27 and the lesser flow through inlet 28, the power cylinder should move cam 96 to the right, and the roller or ball 95 of valve 90 will rise, while the ball or roller 95 of valve 91 will be forced downward to further restrict the flow.

Referring to FIG. 16, there is illustrated a still further embodiment of a non-position seeking rotary hydristor, which is related to the rotary hydristor of FIG. 3, but differs in its construction in that the body 51A is provided with a single outlet port 56 at the bottom of the body, and the internal rotating body 55A is eccentrically mounted with respect to body 51A on shaft 52A. That is internal body 55A will rotate concentrically about its axis. The internal body 55A is provided with two inlet bores 57' and 58'. The inlet bores are in turn connected to a pair of radial bores 57'' and 58'', the radial bores extending to the periphery of the internal body 55A. The inlet bores 57' and 58' are connected to a ratio flow divider (not shown). Thus, in operation, if there is an equal flow to each inlet port the internal body 55A will assume a balanced position with the radial bores 57'' and 58'' in a horizontal position, showing equal clearance between the internal body and external body on either side. However, in the event the flow through inlet port 57' is more than the flow through the inlet port 58', the internal rotor 55A will assume a position as illustrated in FIG. 16, and thus produce a rotary motion indicating the unbalance. It is this rotary movement that is utilized to indicate the change in flow produced by the ratio flow divider.

Referring to FIG. 17, there is illustrated a still further embodiment of a non-position seeking hydristor. This is similar to FIG. 1, except that the piston 11' is provided with a threaded external periphery and the internal surface of the cylinder 10' is similarly threaded to permit a rotary movement of piston 11'. Thus even though this construction provides effective areas for the fluid pressure that will be produced on either side of the piston, the loads or pressures would be absorbed by the threads, and although this embodiment illustrates a threaded element, it is to be understood that there will be sufficient clearance at the crests and roots of the threads to permit a fluid flow therethrough. Thus, with inlet ports 16 and 17 similar to FIG. 1, the fluid flow to either side of piston 11' will permit a seepage or leakage past the threads to the outlet port 15. The piston 11' will react to equal pressures or variance of pressures in the same manner

as the piston 11 of FIG. 1. In FIG. 17, if the helix of the external thread of the piston is made big enough, the unit will become a position seeking hydristor. The rotary portion of the motion provides feed-back for more than 360°.

It is obvious that the design and construction of the hydristor may be varied and many different forms may be utilized. However, in all of the forms described, there are two complementary resistances that are a function of displacement of a member to be regulated by these resistances and in all instances have two pressure ports and one return port, with the exception of the FIG. 14 modification which has two return ports.

Referring to FIG. 18, there is illustrated a schematic of a power system using either a non-position seeking or a position seeking hydristor. For example, using the position seeking hydristor 10, not load compensated, of FIG. 1, the ratio flow divider 30 and the pump 40 in the same sequence, we may add a power cylinder 70 with a piston 71 mounted therein, in which the piston 71 is provided with a connecting rod 14 and in which rod 14 extends through sealed bearings at either end of the cylinder 70 and in which rod 14 is either connected to or is the same rod 14 extending from hydristor 10. Cylinder 70 is provided with two ports 72 and 73 at either end thereof. Ports 72 and 73 are in turn connected to the same lines extending from the ratio flow divider 30, that is port 72 of the cylinder 70 may be connected to the same port 33 of the ratio flow divider as is the line to the hydristor, while port 73 of the power cylinder may be connected to port 34 of the ratio flow divider, the same port that is connected to the opposite end of the hydristor. Thus with the operation of pump 40, when the ratio flow divider is in a central position to divide the flow equally, the fluid flow to the hydristor and similarly to the power cylinder 70 will produce a movement of piston 11 of the hydristor to a central position and at the same time movement of piston 71 of the power cylinder to a central position. It is obvious that any input signal on the ratio flow divider that shall change the ratio flow produces the same change of flow to both the hydristor and the power cylinder so that they will work simultaneously to correct their position. It is obvious that the effective areas of the hydristor, if position seeking, will simply be added to the effective area of the actuator (piston) of the power cylinder. In this system, the position error is sensed because $P1 - P2$ exists but is not compensated.

It is also to be noted in FIG. 18 that a position seeking hydristor system, not load compensated system, can be created with a non-position seeking hydristor. This particular system demonstrates the interrelation between the two hydristor types (position seeking and non-position seeking) because there is added an effective area to the non-position seeking hydristor. Such a system will find application where large, not load compensated, forces have to be created. This system has a much higher volumetric efficiency than the single position seeking hydristor; this is due to the fact that the effective area of a connected actuator can be increased at will.

It is also of interest to note that by reversing the hydristor, that is reversing the fluid flow, using the outlet port as a single pressure port and the two inlet ports as two outlet ports, the hydristor becomes a ratio flow divider and it is also to be noted that with this form of ratio flow divider utilizing the position seeking type of hydristor, the operator who shall actuate the input signal is provided with a resistance or feel on the operating rod.

The hydristors as above described may also be used as a feed back element in a hydraulic servo system.

Referring to FIG. 19, there is illustrated a schematic of a servo system utilizing the position seeking type hydristor as a feed back element. This is comprised of the same cylinder 10 of FIG. 1, with the piston 11 and piston rods 12 and 14, with the cylinder 10 connected by its inlet ports 16 and 17 to ratio flow divider 30,

and the ratio flow divider, in turn, being connected to a pump 40. However, in this instance, the two fluid lines connecting inlet ports 16 and 17 to the flow divider 30 are provided with a null unit 60, which is in the form of a single enclosed cylinder with spring centered diaphragm, the lines being intercepted to pass into and out of either end of the cylinder 60. A single piston 64 is mounted in the center of cylinder 60 to divide this fluid flow on either side of the cylinder. Piston 64 is also provided with a pair of piston rods 62 and 63, which extend through and out of either end of cylinder 60. It is apparent that piston 64 becomes a sensing element that is moved in either direction depending upon the pressures on either side of said piston, and such movement is reproduced by the piston rods 62 and 63.

In FIG. 19 it is to be noted that one end of cylinder 10 is joined to an enlarged power cylinder 70, the power cylinder 70 being provided with a piston 71 and two ports 72 and 73 at either end of said cylinder. It is also to be noted that the piston rod 12 of cylinder 10 extends through the power cylinder and is affixed to the piston 71 and is moved with the movement of piston 71 of the power cylinder and piston 11 of the hydristor. The power cylinder 70 is also connected by means of its ports 72 and 73 to a power hydraulic pump 75, that is hydraulic fluid under high pressure and proper volume is supplied by this pump 75 through an amplifier valve 76. Valve 76 is a five ported valve with a closed cylindrical core 77, and a double piston 78 mounted therein. Piston 78 is actually two pistons, 79 and 80, fitted to the cylindrical core but connected by a central core of lesser diameter. The fluid from said pump 75 passes through an inlet 81 at the center of said valve to surround the lesser diameter of the piston. With the piston 78 in its central position, the outlet ports 82 and 83 are closed. Piston 78 is also connected by the rod 63 extending through the body and attached to rod 63 of the null unit 60. Thus, with movement of piston 64 of the null unit 60, the double piston 78 of valve 76 may be effected to move piston 78 in either direction, and the slightest degree of movement in one direction, for example to the left, will open port 82 to permit a flow of fluid from pump 75 through valve 76, through port 82, to inlet port 73 of the power cylinder. The opposite side of the power cylinder will expell fluid through port 72, through the opposite line to the opposite port 83 of valve 76, which is in turn connected to return port 84. Similarly, if piston 78 had been moved in the opposite direction, fluid would be expelled through the opposite return port 85.

Referring to FIG. 20, there is illustrated a schematic partially in cross-section of a servo system somewhat similar to FIG. 19; however, in this embodiment there is added a subsystem 100, which is, in fact, the hydristor system illustrated in FIG. 1. However, pump 40 must be connected to both the ratio flow divider 30' of the servo system and to the combined null unit and amplifier valve 101 and to the ratio flow divider of the subsystem 100, and in this instance connecting rod 14 of the hydristor 10 is connected to the actuator signal input rod 38' of the ratio flow divider 30' of the servo system. Thus, the signal input or control rod 38 of the subsystem 100 becomes the controlling element for the complete system. A non-position seeking hydristor 20A is shown, this can be used as a feed back device. When a position seeking hydristor is used a resisting force will be acting against loads before power correction takes place. In FIG. 20, the hydristor 20A is somewhat similar to the hydristor shown in FIG. 2 except for the fact that piston 21A has only one piston area 22A and the piston has a hollow center connecting both end chambers. There is no effective pressure area acting on this piston. It is a non-position seeking hydristor. The combined null unit and amplifier valve 101 is a single cylinder closed at both ends and provided with a piston 78' as well as two opposed control inlet ports I and I' and one main

inlet port I'' , also two pressure ports P and P' that are connected by fluid lines to either side of the power cylinder 70 . There are also two exhaust ports O and O' . The piston $78'$ is divided into four cylinder engaging areas or lands, $C1, C2-C3$ and $C4$, with trapped chambers $T1, T2$ and $T3$. Main inlet port I'' is situated centrally within chamber $T2$. Pressure ports $P1$ and $P2$ are aligned with areas or lands $C2$ and $C3$ when the piston is centrally positioned. Exhaust ports O and O' are connected to the trapped chambers $T1$ and $T3$.

The operation of this unit may be followed starting with actuation of the signal input rod 38 of unit 100 . Movement of the input rod 38 will change the fluid flow to cylinder 10 , that is movement of rod 38 to the right or left unbalances the balanced flow. Assuming that rod 38 is moved in to the right, the greater flow will be to the lefthand side of cylinder 10 and the lesser flow to the righthand side; thus, rod 14 will be moved to the right and thus affect the ratio flow divider 30 of the servo system. The effect will be similar, causing a greater flow through the lefthand side of the ratio flow divider and a lesser flow through the righthand side, thus the fluid flow to the lefthand side of the hydristor $20A$ will be greater while there will be a lesser flow of fluid to the righthand side of hydristor $20A$. Likewise, there will be a greater flow through inlet I to the amplifier valve 101 and a lesser flow through inlet I' , thus, the piston $78'$ will move to the right and the fluid flow from pump 40 through inlet I'' will flow through pressure port P' to the lefthand side of power cylinder 70 , creating a power stroke of the piston toward the right, and of course moving piston $21A$ in a similar fashion. The pistons of cylinder 70 and $20A$ will move a predetermined degree, at which time a balance will again exist; that is, with a movement of the piston in power cylinder 70 , there will be a return flow out of the opposite side of the cylinder and the amplifier valve piston $78'$ will also assume a position at which the pressures will again balance. It is apparent that actual control of the power cylinder and the hydristor $20A$ may be maintained with the input rod 38 of the sub-system 100 .

Although applicant is primarily interested in a hydraulic servo system similar to that illustrated in FIGS. 19 or 20, it is to be understood that various changes or modifications may be made in the components of the system, without departing from the spirit of this invention. In every instance there must be a hydristor used. In FIG. 19 there is shown a position seeking linear type hydristor, in FIG. 20 there is shown a non-position seeking linear type hydristor. A rotary hydristor, such as that illustrated in FIGS. 3, 12 or 16 may be similarly used, or a modification of the non-position seeking hydristor, FIG. 2, may also be used, or a porous type linear position seeking hydristor, FIG. 11, may be used, or a non-position seeking linear type of a different design, shown in FIG. 14, may also be used. In every instance, a pump and ratio flow divider shall also be necessary; in fact, the components shown in FIG. 1 are the necessary elements for every system.

It is apparent, referring to FIG. 1, that the signal input rod 38 creates two complementary resistances as a function of position, $R1$ and $R2$; it also creates two flows, $Q1$ and $Q2$. This flow also creates two internal pressures on effective areas of null unit to sense the pressure differential $P1-P2$. Thus, this invention takes advantage of the pressure differential $P1-P2$ in conjunction with the hydraulic element which we call hydristors, as the feed back criterion for control of the position and load of an actuator.

In FIG. 20 we utilize an amplifier valve to convert the feed back and control signals into power motion. It is apparent that by variations and combinations of these elements that novel systems may be created, but in each instance, a hydristor, null unit and pump is used. Whether we used a position seeking hydristor or non-

position seeking hydristor, the same results may be obtained, and with a position seeking hydristor, whether we used a linear or rotary type, the same results may be obtained; and, similarly, with a non-position seeking hydristor, we may use a linear or rotary type. When using a linear or rotary type hydristor, the same principle of leakage over piston clearance may be the controlling factor, or it may be leakage through slots and piston, or it may be leakage through slots in the housing, or it may be leakage through a porous medium, or it may be leakage over tapered or eccentric lands to control the fluid flow. With a linear type hydristor, the direction of leakage is axial, while with a rotary type, the direction of leakage is circumferential (plus leakage through side plate clearance).

Although we have shown the ratio flow divider as the signal input unit for positioning the position seeking hydristor (because the displacement of the ratio flow divider is usually very small), in FIG. 22 we may reverse their relationships, that is the pump P will be connected directly to the port 15 of cylinder 10 , and the fluid flow becomes a reversal of that shown in FIG. 1, and in similar fashion every modification disclosed herein permits this reversal of relationship between the two units.

What is claimed is:

1. A hydraulically positioned servo system which includes a hydristor, said hydristor comprising a cylinder with a reciprocable piston mounted in a central position therein, said cylinder provided with inlet ports and an outlet port, said piston provided with an exterior surface and being loosely fitted within said cylinder to allow two complementary flows over said piston surface from either of the inlet ports to said outlet, said servo-system divided into a power stage and a feed back control stage, said power stage comprising a power cylinder and piston, a main pressure source and a four way valve, said feed back control stage comprising an auxiliary power source, a controlling ratio-flow divider, a differential pressure sensing means, which is mechanically connected to said four way valve, and said hydristor, said hydristor having its piston mechanically connected to the moving piston of said power cylinder as a feed back element, said ratio-flow divider comprising a closed cylinder with an inlet port at its center and two outlet ports, one at each end of said cylinder, a piston and rod mounted loosely and centrally within said cylinder, said rod providing the means for a mechanically produced input signal, said piston rod extending through said cylinder, said piston provided with cone shape faces on either side to reduce its effective area exposed to the fluid pressure flow, said differential pressure sensing device comprising a closed cylinder with two inlet ports and two outlet ports, one inlet and one outlet port connected to each end of said cylinder, a dividing piston with its piston rod extending through said cylinder, and a resilient element positioned on either side of said piston to normally retain said piston balanced.

2. A hydraulically positioned servo system according to claim 1, in which the control flow is divided by the controlling ratio flow-divider into two complementary flows which are connected to either end of said hydristor, said differential pressure sensing means positioning said four way valve to regulate the flow of fluid from the main pressure source to the power cylinder proportional to the pressure differential effect of the complementary flows.

3. A hydraulically positioned servo-system according to claim 2 in which the two complementary flows created by the ratio-flow divider are connected to either side of said differential pressure sensing means and in turn to opposite ends of said hydristor so that the flows are exhausted over two complementary piston surfaces, whose ratio is determined by the position of the moving piston of the hydristor which is mechanically connected to the piston of the power cylinder.

4. A hydraulically positioned servo system according to claim 3 in which the mechanically produced input sig-

nal determines the ratio of said complementary flow (in said hydraulic resistor) and the ratio of the two complementary resistances created by the complementary flows represents the hydraulic feedback signal and said differential pressure sensing device and said four way valve represents the regulating means, said regulating means equalizing the ratio of the complementary flow-through of the hydristor with the ratio of the complementary flow of said ratio-flow divider by admitting the proper amount of fluid from the main pressure source to the power cylinder to in turn move the piston of the power cylinder into the desired position.

5. A hydraulically positioned servo-system according to claim 4 in which the pressure sensing device and the four way valve are two separate units whose sensing and valving members are mechanically connected.

6. A hydraulically positioned servo-system according to claim 4 in which the pressure sensing device and the four way valve are combined into one unit.

10

7. A hydraulically positioned servo-system according to claim 1 using as an input signal a displacement element motivated mechanically.

8. A hydraulically positioned servo-system according to claim 1 using as an input signal a displacement element motivated electrically.

9. A hydraulically positioned servo-system according to claim 1 using as an input signal a displacement element motivated by an auxiliary hydraulic system.
